UNITED STATES PATENT OFFICE.

LESTER NEVERS AND FRANK WHITBECK, OF GRAND RAPIDS, MICHIGAN.

BOILER-SETTING.

1,327,727.

Specification of Letters Patent. Patented Jan. 13, 1920.

Application filed April 5, 1917. Serial No. 160,062.

To all whom it may concern:

Be it known that we, LESTER NEVERS and FRANK WHITBECK, citizens of the United States of America, residing at Grand Rapids,

5 in the county of Kent and State of Michigan, have invented certain new and useful Improvements in Boiler-Settings; and we do hereby declare the following to be a full, clear, and exact description of the invention, 10 such as will enable others skilled in the art to which it appertains to make and use the same.

This invention relates to a boiler setting and furnace construction for boilers it being an object and purpose of our invention 15 to produce a device of this character and provide it with various novel constructions by means of which a thorough and complete combustion of fuel in the fire box underneath the boiler may be obtained, there being sub- 20 stantially no smoke given off irrespective of the type or grade of fuel used. Our invention consists essentially in the installation of means through which, when fresh fuel is thrown on one side of the fire, the gases and 25 smoke which immediately arise therefrom are constrained to pass across the opposite side of the fire which, being fully ignited, causes the combustion of gases and smoke so that a complete combustion of the fuel is at- 30 tained. In addition our invention has for its object the heating of air before it comes to the fire whereby a more perfect combustion and greater heat is obtained from the fuel.

35 Our invention by which these ends and many others are attained is illustrated in the accompanying drawings in which;

Figure 1 is a vertical section taken through a boiler having our new and improved set- 40 ting.

Fig. 2 is a section taken substantially on the line 2—2 of Fig. 1.

Fig. 3 is a front elevation.

Fig. 4 is a partial vertical section and 45 front elevation of the boiler and setting therefor and,

Fig. 5 is a section reduced in size and taken substantially on line 5—5 of Fig. 1.

Like reference characters refer to like 50 parts throughout the several views of the drawings.

The boiler 1, shown as of water tube type, is supported at its ends by front and rear walls 2 and 3 while at each side of the boiler 55 vertical walls 4 are placed to inclose the same. A steam drum 5 is located above and

connected with the boiler as shown, it of course being understood that the particular type of boiler is not in any way an essential feature of our invention.

60

The fuel is received on the grate 6, being entered alternately into the fire box above the grate through the two front doors 7 and 8. The ash pit 9 is located below the grate, entrance thereto at the front being through 65 a door 9^a. The fire box has an arched cover 10 below which at the rear is a post 11 preferably of the cross section shown in Fig. 5. The ash pit rear wall 12 is located across the front end of an air conduit 13 which is 70 inclosed by sides 14 and 15 and a cover 16, this conduit at its rear end turning at right angles, as indicated at 13^a, being there inclosed by a side 17 and rear wall 3 with cover 16 extended thereover. The end of 75 the branch 13^a is in communication with the outer air as indicated in Fig. 2. At its front end the air conduit 13 has oppositely extending branches 18 and 19 which are located back of the rear of the wall 12 and are then 80 turned forwardly as shown at 20 and 21 said conduits 20 and 21 being inclosed by the sides 22 of the fire box, the walls 4 of the boiler setting and a cover thereover in alignment with the grate 6 as shown in Fig. 4. 85

In the branch conduits 20 and 21 pipes 23 are located, at their front ends extending in front of the boiler setting and in communication with vertical pipes 24 which are connected in any suitable manner with 90 the steam drum 5 to receive steam. At a number of points in the length of the pipes 23 branches are made and turned upwardly as indicated at 26 being received in spaces formed in the side walls 4 and extending 95 upwardly to points above the grate. Said spaces have openings 27 communicating with the fire box at points above the grate.

After the fire on the grate 6 has been started and is burning freely new fuel is put 100 on the fire at one side only. For instance, it may be thrown on to the fire through the door 8 at the right. When this is done steam is passed into the pipe 23 on the same side of the fire either by turning the proper valve 105 or by any automatic arrangement operated by opening of the door. The steam passing through the pipe escapes through the various branches 26 and passes through openings 27 over the freshly entered fuel at the 110 same time producing a suction which draws the air from the conduit 13 through the

branches 19 and 21, the combined air and steam passing over the fresh fuel and carrying the gases and smoke which rise therefrom to the left side of the fire. Post 11 is 5 of utility in this connection in blocking the escape of the gas and smoke before they pass over the fire at the left of the furnace yet at the same time it is not of sufficient size to impede the progress of the products of 10 combustion to the rear. Such smoke and gases accordingly are entirely consumed and back of the post 11 no smoke appears. It will also be evident that by reason of the heat upon the conduit 13 the air passing 15 therethrough is warmed and heated considerably above ordinary atmospheric temperature before it reaches the fire.

The same operation is gone through with 20 at the next firing of the boiler but on the opposite side of the fire, the steam being admitted through the pipe at the opposite side so that, at all times, as fresh fuel is placed on the fire, the usual smoke and gases arising are forced to pass over the freely burning fuel on the other side of the furnace to 25 be completely consumed and the entire heat of the fuel utilized.

We claim:—

1. In combination with a boiler, a setting 30 therefor forming a fire place under the boiler and provided with an arch, said fire place being provided with an outlet, a grate in the fire place, a post located at the back of the fire place and centrally of the same 35 and dividing the outlet in the fire place into two passages, fire doors located on opposite sides of the middle of the front to enable the side portions of the fire place to be alternately supplied with fresh fuel, means for 40 introducing heated air into the fire place at the sides thereof above the grate, and steam pipes located at the sides of the fire place and having outlets discharging into the fire place and arranged to draw heated 45 air into the same, the steam outlets on each side of the fire place being adapted to force the smoke and gases from one side of the fire place to the opposite side thereof.

2. In combination with a boiler, a setting 50 therefor, a fire place arranged under the boiler and provided with an outlet, a grate in the fire place, an upright post located centrally in the rear of the grate and dividing the outlet of the fire place into two 55 passages, firing doors located on opposite sides of the middle of the front to enable the sides of the fire place to be alternately supplied with fuel, an air inlet flue provided with branches extending to the sides of the 60 fire place and along the same and provided with outlets communicating with the fire place above the grate and steam pipes having outlets discharging into the fire place at the said outlets of the branches of the 65 air passage, the steam outlets on each side of

the fire place being adapted to force the smoke and gases from one side of the fire place to the opposite side thereof.

3. In combination with a boiler, a setting 70 therefor forming a fire place under the boiler, said fire place being provided with an outlet, a grate in the fire place, an upright post located centrally in the rear of the grate and dividing the outlet of the fire place into two passages, firing doors located 75 on opposite sides of the middle of the front to enable the sides of the fire place to be alternately supplied with fuel, an air inlet flue located in the rear of and extending forwardly to the fire place and provided 80 with branches extending laterally to the sides of the setting, and forwardly along the side of the fire place and provided with outlets 85 communicating with the fire place above the grate and steam pipes discharging through the said outlets into the fire place and adapted to draw heated air from the flue into the fire place, the steam outlets on each side of the fire place being adapted to force the smoke and gases from one side of 90 the fire place to the opposite side thereof.

4. In combination with a boiler, a setting 95 therefor forming a fire place under the boiler, said fire place being provided with an outlet, a grate in the fire place, an upright post located centrally in the rear of the grate and dividing the outlet of the fire place into two passages, firing doors located 100 on opposite sides of the middle of the front to enable the sides of the fire place to be alternately supplied with fuel, an air inlet flue located in the rear of the grate and having branches extending to the sides of the setting and forwardly along the sides of the fire place below the plane of said grate and 105 provided with upwardly extending outlets communicating with the fire place above the grate and arranged at spaced points, and steam pipes located in said branches below the plane of the grate and having branch 110 pipes extending upwardly in the said outlets and arranged to discharge into the fire place through the said outlets, and the steam outlets on each side of the fire place being 115 adapted to force the smoke and gases from one side of the fire place to the opposite side thereof.

5. In combination with a boiler, a setting 120 therefor forming a fire place under the boiler, said fire place being provided with an outlet, a grate in the fire place, an upright post located centrally at the back of the fire place and dividing the outlet thereof into two separate passages, said post being provided at its front portion with forwardly converging side faces, fire doors located at the front of the fire place on opposite sides of the middle of the front to enable the sides of the fire place to be alternately supplied with fuel, an air inlet flue 125

- located in the rear of the grate and having branches extending to the sides of the setting and forwardly along the sides of the fire place below the plane of the said grate and provided with upwardly extending outlets communicating with the fire place above the grate and arranged at spaced points, steam pipes located in the said branches and below the plane of the grate and having branch pipes extending upwardly in the said outlets and arranged to discharge into the
- fire place and draw heated air from the flue into the said fire place, the said steam outlets on each side of the fire place being adapted to force the smoke and gases from 15 one side of the fire place to the opposite side thereof.

In testimony whereof we affix our signatures.

LESTER NEVERS.
FRANK WHITBECK.
